UNITED STATES PATENT OFFICE.

HENRY J. SAGE, OF BEAVER, PENNSYLVANIA.

GLASS-CUTTING APPARATUS.

SPECIFICATION forming part of Letters Patent No. 728,417, dated May 19, 1903.

Application filed March 22, 1901. Serial No. 52,333. (No model.)

To all whom it may concern:

Be it known that I, HENRY J. SAGE, of Beaver, in the county of Beaver and State of Pennsylvania, have invented a new and useful Glass-Cutting Apparatus, of which the following is a full, clear, and exact description, reference being had to the accompanying drawings, forming part of this specification, in which—

10 Figure 1 is a side elevation, partly broken away, showing glass-cutting apparatus constructed in accordance with my invention. Fig. 2 is an end elevation of the same, partly broken away. Fig. 3 is a plan view of the same. Figs. 4 and 5 are detail views, on a larger scale, showing the manner of mounting the diamonds. Fig. 6 is a view similar to Fig. 4, showing a modified construction. Fig. 7 is a similar view of another modification, and Fig. 8 is an enlarged detail view of the pawl mechanism for lifting the cutter-bar.

15 My invention relates to the cutting of large glass sheets into smaller plates or sheets and is designed to do away with the operation of hand-cutting as now carried out. This hand-cutting is not only very expensive, demanding highly-skilled labor, but also gives a large percentage of breakage and waste from imperfect cutting or accidental moving of the gage. My invention overcomes these difficulties and greatly reduces the cost; and it consists in apparatus for simultaneously making a plurality of cuts or scorings of the glass.

20 It further consists in a series of yieldingly-pressed cutting-tools in combination with a glass-carrying table and mechanism for moving the tables and cutting-tools relatively to each other, and, further, in the construction and arrangement of the parts, as hereinafter more fully described, and set forth in the claims.

25 In the drawings, in which I show one form of my invention, 2 is a rotary table mounted on a spider 3, having a stem, formed in two parts 4 and 5, having screw-threaded connections with each other, the lower part being supported on a cam 6. A lock-nut 7 is employed to secure the stem in any adjusted position, and a roller 8 at the lower end of the stem bears on the lifting-cam.

A framework 9 is carried on standards 10

beneath the table, the stem of the table extending through a bearing in the frame and also through a lower bearing 11, carried upon lateral extensions of depending legs 12, secured to the frame. The cam is mounted upon a shaft 13, having a pinion 14 intermeshing with a toothed wheel 15, which latter is an idler-wheel and engages a pinion 16 upon a shaft 17, at the other end of which is mounted a large internal cam 18. The shaft 17 is mounted in suitable bearings 19 and with the cam 18 engages a roller 20, mounted on a slide 21, carried in a bearing 22 and having link connection 23 with a toothed segment 24. The teeth of this toothed segment engage with a pinion 25, mounted on shaft 26, extending transversely of the table, and this shaft is provided with toothed wheels 27, engaging racks 28, secured to the brackets 30 of the cross-head 29, extending across the table. This cross-head 29 is carried upon brackets 30, having shoes 31 secured thereto and movable on tracks 32, formed as part of a rail 33. The bracket proper is provided with a lower flange 34, which projects laterally under the head of the rail and holds the cross-head in place in its movements.

30 The transverse bar of the cross-head 29 carries the diamond-holders, which are similar to each other and which I have shown as follows: Each holder 35 is formed in two parts, which are bolted together about the bar 29, which fits in recesses therein, and from one half of the holder project the arms 36, having angular holes in vertical registry and containing an angular slide 37. A spiral spring 38 surrounds the slide and is confined between an adjustable collar 39 and the upper arm 36. This spring constantly tends to force the diamond-holder down, and its downward movement is limited by a stop 40. These stops are the same in number as the number of diamond-holders and engage 45 forked lever 41, engaging pins 42 on an adjustable collar 43, secured to the sliding diamond-holder. The levers 41 are secured to a common rock-shaft 44 by means of set-screws 45, entering a keyway in this shaft, and at the end of this shaft is secured a lever 46, having a pawl 47 pivoted thereto. This pawl is normally pressed down by spring 48, so that its front end engages a notch in an arc-

shaped plate 49, secured rigidly to the bracket 30. This plate contains two notches, each arranged to receive the pawl, which being spring-pressed will engage either of them 5 when registering with it.

The lever 46 is immediately above the end of the sliding rod 50, sliding through bearings in brackets 51 and 52 and having a roller bearing on cam 53. The roller is held 10 against the cam by spring 53', and the cam is provided with two oppositely-extending projections, as shown in Fig. 1. The pawl is immediately above a similar sliding rod 54, whose lower roller rides on an inner cam 55, 15 mounted on the same shaft 56 as the cam 53 and having projections similar to but higher than those of cam 53. The main power-shaft 56 is provided with a gear-wheel 56', which meshes with the pinion 16 and imparts motion thereto and to the other gears of this train. By this mechanism I can automatically change the width of the cuts at each successive movement of the cutters. Thus as the cutter-carrying cross-head is moved in one 20 direction the cams engaging the rollers on rods 50 and 54 will first lift the pawl to disengage it from its lower notch and then lift the lever, thus swinging the rock-shaft and elevating the cutters after the cuts have been 25 made. Now having locked the levers 41 of alternate ones of the cutters, as the cam projections pass the rollers of the sliding rods the pawl will be released and its spring will force it into the upper of the notches. The 30 lever then being released is locked in its upper position by the pawl, and consequently all of the levers 41, which are locked to it, will be held against downward movement and will retain their cutters in lifted position, 35 as illustrated in Fig. 5. On the next forward movement of the cross-head, therefore, only those cutters will operate whose lifting-levers have not been secured to the rock-shaft. As the cross-head reaches the end of 40 its return stroke, coming back to its normal position, the cams 53 and 55 will again operate the pawl and the lever and will release the pawl and allow the lever to fall, the cam 55 operating in advance of the cam 53, so 45 that the pawl will be operated before the lever is allowed to drop. The pawl enters the lower notch and allows the rock-arm to swing down, so that all the cutters will engage the glass when the table is raised for 50 cutting the next sheet.

In order to adjust the distance between the diamond or cutting wheels, I provide a screw-threaded shaft 57, which extends beneath the rock-shaft and through holes at the lower 55 ends of the cutter-holders. Lock-nuts 58 engage each cutter-holder, and by loosening one of these nuts and tightening the other the holder may be moved along the cross-head and then secured by tightening these lock-nuts. 60

At the lower end of the sliding stem 37 is secured a plate 59, having pivoted thereto a

swinging plate 60, with an arc-shaped slot through which a screw-threaded stem extends from the plate 59, carrying a thumb-nut 61, by which the swinging plate may be secured in any adjusted position. Each swinging plate is provided with a stem 62, projecting downwardly and entering a ferrule 63, adjustably secured to it by set-screw 64. The diamond or other cutting tool is secured at the lower end of the ferrule 63, and it is evident that by turning the ferrule on its stem and swinging the plate portion of the stem a universal adjustment is afforded 80 to bring the cutter to any desired position, in which it may then be locked.

To facilitate the cutting operation and better the action of the diamonds, I prefer to oil the plates along the paths traveled by the 85 diamonds, and to perform this function I secure to the plate 59 an arm 65, having a wick-holder 66 adjustably secured therein by set-screws 67, this wick-holder leading down from an oil-reservoir 68. This reservoir may 90 have a cap 69, and a screw 70 is provided, which will press upon the wick and regulate the flow of the oil or other lubricant. This oiler being secured to the sliding stem of the cutter-holder will rise and fall with it. 95

In order to raise an individual diamond or cutting tool when the glass is broken or otherwise desired, I pivot a yoke 71 to pins projecting from the top of each cutter-stem and form one end of this yoke in the form of a 100 cam 72. Each yoke is provided with a handle 73, and by throwing this handle in the position shown in dotted lines in Fig. 4 the diamond will be lifted and prevented from cutting. 105

In order to revolve the table, if desired, in case transverse cuts are to be made after the longitudinal cuts, I mount on the shaft 56 at its inner projecting end an interior cam 74, which is engaged by a roller 75 on a sliding 110 rod 76, movable in bearings 77 and having rack-teeth engaging a pinion 78, secured to the table-stem. The cam is shaped as shown in Fig. 1, so that after the table has been given its forward stroke, thus cutting the 115 glass longitudinally, the roller or slide 76 will engage the actuating part of the cam, and thus move the rack endwise and turn the table through ninety degrees. The roller then enters the arc-shaped portion of the cam and 120 continues therein during the return stroke of the table, and to stop the table and lock it in its correct adjusted position after turning I provide a spring-pressed pin 79, which slides vertically in bearing 80 and is normally pressed upwardly by spring 81. A link 82 pivotally connects the lower end of this pin with lever 83, pivoted to the frame at 84 and having roller 85 bearing upon cam 86, mounted on shaft 13. This cam is provided 125 with one projection 87, which is timed to retract the pin at the end of the forward stroke and just before the rack begins to turn the table. 130

In operating the apparatus the diamond-cutters are secured to or unlocked from the rock-shaft, according to the width of the cuts desired on the second cutting stroke. The 5 glass plate is then laid upon the table, which is lowered away from the cutters, and properly positioned and held thereon by small pins 88, against which the sheet may be moved by small hand-actuated cams 89, as shown in 10 Fig. 3. The machine then being started into operation, the table is raised, the cutter-carrying cross-head is moved lengthwise of the table, and the spring-pressed diamond-tools, or such as are not locked in upper position, 15 travel in parallel lines across the glass sheet and score it in the usual manner. After the cross-head has reached the end of its travel the locking-pin 79 is withdrawn, and the table is first lowered and then turned through 20 ninety degrees and the locking-pin released to clamp it in its adjusted position. The cutter-carrying cross-head is then automatically moved on its return stroke, and at the end of this stroke the table is automatically raised 25 to cause the glass to contact with the cutter, and such of the cutters as are locked to the rock-arm will be held in upper inoperative position by raising the lever 46 and locking it to pawl 47 in the upper notch in the locking-plate 49. The table then starts on its 30 forward cutting stroke, and the same cycle of operations as above described follows, except that at the end of the second backward stroke of the cross-head the cam releases the locking device for the tools and allows all the 35 tools to descend to the cutting position. At the end of the second forward or cutting stroke of the cutters the table is turned ninety degrees, but in the opposite direction to its motion at the end of the first stroke, so that at 40 the end of the second return stroke the parts all resume their normal positions.

In the form above described it is evident that the distance between the cuts must always be the same as or a multiple of the space 45 between the cutting-tools. To overcome this difficulty and provide for cutting any width desired, I may duplicate the system of tools as shown in Fig. 6. In this figure similar numerals indicate corresponding parts to those of the previous form having the prime-mark applied thereto, and to the rock-shafts 44' I secure pinions 90, which intermesh with an intermediate pinion 91 on a shaft 92, which 50 may be provided with a handle or crank and a pawl or other locking mechanism. By turning this handle either set of tools may be alternately withdrawn from the cutting position, as shown in the figure, and by thus combining the cutting of one set of tools with that of the other, with the adjustments of each, I can obtain any desired width between the 55 cuts.

The apparatus above described is especially designed for cutting large quantities of pieces or plates of the same size with great accuracy; but where it is desired to frequently

change the sizes of the plates I may provide the cross-head with a scale, as shown in Fig. 7, and simply secure the diamond-holder 70 thereto by an adjustable set-screw 93. This greatly simplifies the mechanism and is adapted for smaller work on a large quantity of different sizes.

In order to change the length of the cut, I 75 provide a bell-crank lever 94, which is connected through pivotal link 95 with the link 23, the end of which link is adjustable in a radial slot of the toothed segment 24. By swinging the bell-crank lever the link 23 may 80 be adjusted to different portions of the slot, and the length of the cut may thus be adjusted as desired.

The advantages of my invention will be apparent to those skilled in the art. The large 85 expense of cutting, which has heretofore considerably increased the cost of all kinds of sheet and plate glass, is greatly reduced. The cutting is done more accurately than it can be done by hand, and the percentage of 90 waste and breakage is greatly reduced. In actual practice the device is found to work with great efficiency, giving accurate results and an enormous output.

The apparatus lends itself readily to cutting any and all shapes. For example, by swinging the table through different arcs any angles desired may be cut, and arcs or circles may also easily be cut during the rotation of the table. Many other changes in the form and arrangement of the parts may be made without departing from my invention, since I consider myself the first to mechanically cut glass with a plurality of simultaneous scorings. 105

I claim—

1. In glass-cutting apparatus, a table for the glass, a cutter-support having a plurality of cutters carried thereon, said cutters being movable at right angles to the plane of the 110 table, mechanism for imparting a yielding pressure to the cutters, and mechanism for moving the table and support relatively to each other; substantially as described.

2. In glass-cutting apparatus, a glass-carrying table, a support having a series of spring-pressed cutter-carriers thereon, mechanism for moving the table and cutter-carriers toward and from each other, said cutters being movable at right angles to the plane of the 120 table, and mechanism for moving the table and cutter-carrier longitudinally of each other to effect the cut; substantially as described.

3. In glass-cutting apparatus, a turning glass-carrying table, a support having a series of cutter-carriers mounted thereon and movable at right angles to the plane of the table, mechanism for pressing the cutters toward the table with a yielding pressure, and mechanism for turning the table; substantially as described. 125

4. In glass-cutting apparatus, a glass-carrying table, a support having a plurality of spring-pressed cutter-carriers movable at

- right angles to the table, mechanism for moving the cutter-support and table toward and from each other, mechanism for turning the table, and mechanism for moving the support 5 and table longitudinally of each other during the cutting operation; substantially as described.
5. In glass-cutting apparatus, a glass-carrying table, a support having a plurality of 10 adjustable yieldingly-pressed cutters thereon and movable at right angles to the table, and mechanism for moving the table and cutter-carrier relatively to each other; substantially as described.
15. 6. In glass-cutting apparatus, a turning table for the glass, a support having a series of adjustable spring-pressed cutters movable at right angles to the table, mechanism for moving the table and cutter-carriers toward 20 and from each other, and mechanism for moving the table and cutter-carrier longitudinally of each other; substantially as described.
25. 7. In glass-cutting apparatus, a glass-carrying table, a support having a series of yieldingly-pressed cutters, a retracting device arranged to act upon all the cutters, and mechanism for connecting or disconnecting the cutter-carriers from said retracting device; substantially as described.
30. 8. In glass-cutting apparatus, a glass-carrying table, a support having a series of yieldingly-pressed cutters, and mechanism for adjusting the spaces between the cutters; substantially as described.
35. 9. In glass-cutting apparatus, a glass-carrying table, a support having a plurality of spring-pressed cutter-carriers mounted thereon and movable at right angles to the plane 40 of the table or support, and mechanism for adjusting the pressure of the springs; substantially as described.
45. 10. In glass-cutting apparatus, a glass-carrying table, a support, a plurality of cutter-carriers secured thereto and movable at right angles to the plane of the table or support, and mechanism for adjusting the angle of the cutter-carriers relatively to the plane of the sheet; substantially as described.
50. 11. In glass-cutting apparatus, a glass-support, a cutter-support having a plurality of cutter-holders secured thereto and movable at right angles to the plane of the table or support, and mechanism whereby the holders 55 may turn on their axes; substantially as described.
60. 12. In glass-cutting apparatus, a glass-carrying table, a support having a plurality of cutter-carriers mounted thereon, and mechanism whereby the carriers may turn in three directions; substantially as described.
65. 13. In glass-cutting apparatus, a support

having a series of cutter-holders, mechanism for exerting yielding pressure upon said holders, and stops to limit their movements under 65 said pressure; substantially as described.

14. In glass-cutting apparatus, a cutter-holder having a rocking element with a clamp, and a cutter-holding stem revolubly secured to said rocking element; substantially as described. 70

15. In glass-cutting apparatus, a support having a plurality of cutter-carriers, and a lubricating device secured to each cutter-carrier; substantially as described. 75

16. In glass-cutting apparatus, a support having a series of yieldingly-pressed cutter-holders, mechanism for simultaneously retracting all of said holders, and means for retracting part of said holders independently of 80 the other holders; substantially as described.

17. In glass-cutting apparatus, a glass-carrying table, a support having a plurality of cutter-carriers arranged to give parallel cuts, mechanism for exerting a yielding pressure 85 upon the cutters, means for holding the cutters in retracted inoperative position, mechanism for moving the cutter-carrier support and table relatively to each other to form the cutting stroke, and mechanism for automatically turning the table after said cutting 90 strokes are completed; substantially as described.

18. In glass-cutting apparatus, a glass-carrying table, a support having a series of cutter-carriers, mechanism for moving the table and support longitudinally of each other, and mechanism for automatically raising the table before and lowering the same after the cutting stroke is completed; substantially as described. 95

19. In glass-cutting apparatus, a glass-carrying table, a support having a plurality of cutter-carriers, mechanism for moving the table and support relatively to each other, 105 and mechanism for automatically retracting a portion of said cutter-carriers before the second cutting stroke; substantially as described.

20. In glass-cutting apparatus, a glass-carrying table, a support having a plurality of cutter-carriers, mechanism for moving the table and support relatively to each other, mechanism for automatically retracting a part of said cutter-carriers before the second 115 cutting stroke and mechanism for releasing the cutter-carriers after the second cutting stroke; substantially as described.

In testimony whereof I have hereunto set my hand.

HENRY J. SAGE.
